US00D800302S

(12) **United States Design Patent** (10) **Patent No.:** **US D800,302 S**
(45) **Date of Patent:** **** Oct. 17, 2017**

(54) **ABSORBENT ARTICLE WITH A PATTERN**

(71) Applicant: **The Procter & Gamble Company**,
Cincinnati, OH (US)

(72) Inventors: **George Christopher Dobrin**, Mason,
OH (US); **Beth Goldman Mason**,
Cincinnati, OH (US); **Daniel Patrick**
Findley, Finneytown, OH (US);
Timothy Wayne Robertson,
Cincinnati, OH (US); **David Rex Price**,
Indianapolis, IN (US)

(73) Assignee: **The Procter & Gamble Company**,
Cincinnati, OH (US)

(**) Term: **15 Years**

(21) Appl. No.: **29/589,682**

(22) Filed: **Jan. 4, 2017**

Related U.S. Application Data

(60) Continuation of application No. 29/552,612, filed on
Jan. 25, 2016, now Pat. No. Des. 779,658, which is a
continuation of application No. 29/533,211, filed on
Jul. 15, 2015, now Pat. No. Des. 751,698, which is a
continuation of application No. 29/489,610, filed on
May 1, 2014, now Pat. No. Des. 736,910, which is a
division of application No. 29/478,589, filed on Jan.
7, 2014, now Pat. No. Des. 707,813, which is a
division of application No. 29/396,475, filed on Jun.
30, 2011, now Pat. No. Des. 699,838.

CLAIM

The ornamental design for an absorbent article with a pattern, as shown and described.

DESCRIPTION

FIG. 1 is an enlarged, partial development view of the claimed left portion of a first embodiment of an absorbent article with a pattern seen in its entirety in FIG. 3; FIG. 2 is an enlarged, partial development view of the claimed right portion of the first embodiment of an absorbent article with a pattern seen in its entirety in FIG. 3; and, FIG. 3 is a development view of the first embodiment of the absorbent article with a pattern.

The broken lines, including those showing the diaper tabs and ears, are included for the purpose of illustrating environment and form no part of the claimed design.

The claimed design comprises an ornamental surface pattern printed on flat surfaces in the same plane.

1 Claim, 1 Drawing Sheet
